(54) **PAINT, BROWN**

(76) Inventor: **Thomas Miller Jr.**

James A. Miller, Jr.

Letters Patent,

The schedule referred to in these Letters Patent and making part of the same containing a description in the words of the said James A. Miller, Jr., himself of his Manufacturing Bristow Paint,

The paint in its crude state, recently stone and is an earthy substance. It is found in veins below the surface of the earth on the banks of the Bristow Creek and also on the banks of other creeks in Oneida County and in other places in the State of New York, when first dug from the ground the mass adheres firmly together but will remain long exposed to the air, or a time, the particles gradually separate from the mass without any external pressure. The colour is of a light chocolate brown with a purple shade. The shade of colour vary in the same vein & it appears uniformly darker in the lump than when pulverized.

The method of manufacturing it is by drying the substance in an oven and then grinding it, or pulverizing it in some other manner. It mixes readily with oil and forms a bright colour.

Witnesses,

John Lucas,
Samuel Goodwin,
